UNITED STATES PATENT OFFICE.

ARTHUR L. MCKINSTRY, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

1,282,097.

Specification of Letters Patent. Patented Oct. 22, 1918.

Application filed December 18, 1916. Serial No. 137,604.

To all whom it may concern:

Be it known that I, ARTHUR L. MCKINSTRY, a citizen of the United States, residing at Southbridge, in the county of Worcester and State of Massachusetts, have invented certain new and useful Improvements in Ophthalmic Mountings, of which the following is a specification.

My invention relates to improvements in ophthalmic mountings and has particular reference to an improved construction for connecting the parts of such mountings.

The leading and principal object of the present invention is the provision of an improved clamping member or clip especially adapted for use in connecting a non-metallic lens rim or frame with the metallic portion of an ophthalmic mounting.

A further object of the invention is the provision of a fitting of this character which will so inter-engage in the rim as to prevent any relative sliding or twisting movement of the parts.

Other objects and advantages of my improved construction should be readily apparent by reference to the following specification taken in connection with the accompanying drawings, and it will be understood that I may make any modifications in the specific details of construction shown and described within the scope of the appended claims without departing from or exceeding the spirit of my invention.

Figure I represents a front view of a mounting embodying my mounting.

Fig. II represents a sectional view as on the line II—II of Fig. I.

Fig. III represents a plan view of the blank before shaping.

Fig. IV represents a sectional view as on the line IV—IV of Fig. III.

Fig. V represents a plan view of a slight modification of my construction.

Fig. VI represents a sectional view of the same applied to a frame.

In the drawings, in which similar characters of reference are employed to denote corresponding parts throughout the several views, the numeral 1 denotes the metal center or bridge of the mounting, having at each end one of my improved clip or attaching members 2, which serves to secure to the bridge the zylonite or other non-metallic or composition lens frame or rim 3, which has

at its outer side an additional one of my improved attaching devices 4 having the end piece 5 for the temple, 6 which retains the mounting in position on the face.

Previous to my invention it has been customary to make frames of the character just described but certain difficulties have been found in connection with the attachment of the parts due to the tendency of the parts to have a relative twisting or sliding movement allowing the mounting to become slightly shaky and consequently unsatisfactory in use.

It is, therefore, the essential purpose of my present invention to provide a clip which will unite the parts against this loosening or shaky movement while permitting of their ready attachment one to the other, and eliminating the weakening of parts by forming of holes therethrough for screws, rivets or other fastening devices, as has sometimes been deemed necessary in the attempt to get away from this relative loosening of the parts.

In the carrying out of my invention I preferably employ a clip member 2, which may be initially formed as a sheet metal stamping and subsequently curved to substantially U-shape in cross section, as illustrated in Figs. II and VI. In constructing the form of my clip member illustrated in Figs. II to IV inclusive, for example, I preferably shape the inner face thereof as by striking to press up therefrom the integral points or prongs 7, and the recesses or depressions 8, the recesses or depressions 8 being near the end of the clip member and serving a double purpose in that they are adapted both to receive longitudinal ridges forced up from the rim 3 by the application of the clip thereto, and also by creasing the clip on the inner side serve to facilitate bending and shaping of the same to fit the frame member 3.

In use the clip member being suitably formed, it is applied to the frame member 3 with considerable pressure, this pressure being so distributed and being sufficient to cause the prongs 7 to firmly bite into the frame member 3 and the entire clip to become slightly imbedded therein to have a firm clenching or gripping engagement therewith. The pressure applied in this way is sufficient to cause a certain outward expan-

sion of the frame member 3 so that it will fill up the recesses 8 with the ribs 9, as illustrated in Fig. II. As a result the frame is held against longitudinal sliding or twisting 5 by the biting of the prongs or points 7 thereinto, and in addition is particularly braced against lateral twisting and also held somewhat against longitudinal or rotative movement relative to the clip on account of 10 the inter-engagement of the ribs 9 and recesses 8, while the application of the clip produces the raised ribs 9 having if anything a reinforcing effect rather than a weakening as would be the case were the 15 frame pierced or an undue number of prongs biting thereinto employed.

In Figs. V and VI, I have illustrated one alternative form of my construction in which in place of providing the recesses 8 20 I have provided the apertures 10 adapted to receive the bosses or knobs 11, which will be produced from the frame 3 by the pressure of application of the clip thereto, or which may be previously produced on the frame 25 to a greater or less extent and the clip then fitted thereonto.

From the foregoing description taken in connection with the accompanying drawings, the construction and advantages of my 30 improved attaching clip should be readily understood, and it will be seen that I have provided a simple and efficient clip which may be readily applied to a composition frame, which will in nowise weaken the 35 frame but which will very securely and firmly engage the frame to prevent any relative slipping of the parts.

I claim:

1. The combination with a non-metallic 40 lens frame, of a fitting applied thereto under pressure, said fitting having inwardly extending projections inside to bite into the

frame by the force of application of the fitting and having recesses to receive portions of the frame expanding thereinto from 45 the pressure of application of the adjacent portion of the fitting to the frame so as to hold the frame against movement.

2. The combination with a non-metallic yieldable frame, of a fitting therefor having 50 the inner face provided with longitudinally extending grooves whereby as the fitting is applied to the frame under pressure the frame will extend into said grooves and shaping of the fitting around the frame will 55 cause the walls of the grooves to bite against and clampingly engage the ribs thus formed in the frame, and integral prongs upon the interior of the fitting adapted to bite into the frame to retain the same against longitudinal sliding or twisting movement.

3. The combination with a non-metallic frame member, of a fitting therefor having its inner face formed with longitudinally extending grooves disposed to lie near the inwardly curving faces of the frame whereby the fitting may be readily bent to curve around the frame and may be pressed under the frame to cause portions of the frame to expand into the recesses and be subsequently 70 clampingly secured in the recesses by inward curving of the fitting around the frame, and inwardly extending projections on the fitting caused to bite into the frame by the force of application of the fitting 75 and thus to hold the frame securely against longitudinal sliding or twisting movement.

In testimony whereof I affix my signature in the presence of two witnesses.

ARTHUR L. McKINSTRY.
